UNITED STATES PATENT OFFICE.

HARRY McGRAW, OF MARION, INDIANA.

AIR MOTOR.

Application filed June 25, 1921. Serial No. 430,336.

To all whom it may concern:

Be it known that I, HARRY McGRAW, a citizen of the United States, residing at Marion, in the county of Grant and State of Indiana, have invented a new and useful Air Motor, of which the following is a specification.

This invention relates to air motors, and more particularly to a motor operated by a current of air passing through an air conduit which is in communication with a smoke stack or the like.

The primary object of the invention is to provide a wheel disposed in the path of travel of the current of air, whereby the air will act on the blades of the wheel to cause the rotation thereof.

A further object of the invention is to provide means for controlling the passage of air through the air duct, thereby regulating the speed of the wheel.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of a motor constructed in accordance with the present invention.

Figure 2 is a sectional view through the motor chamber and air conduit.

Figure 3 is a sectional view taken on line 3—3 of Figure 1.

Figure 4 is a sectional view taken on line 4—4 of Figure 1.

Referring to the drawings in detail, the reference character 5 designates an air column which has communication with a smoke stack, whereby the products of combustion passing through the smoke stack, will create a vacuum within the column 5 to draw air through the conduit 6 which communicates therewith.

At one end of the conduit 6 is an enlarged motor chamber 7 which is preferably circular in cross section to accommodate the motor or wheel 8, which is provided with blades 9 that lie within the path of travel of air passing into the motor chamber, so that the wheel will be rotated. The wheel or

motor embodies a hub 10 which is supported on the axle 11 that extends transversely through the motor chamber.

The motor chamber is provided with an opening 12 at the upper portion thereof, and an opening 13 at the lower portion thereof, there being provided a guideway 14 to accommodate the sliding closure 15 adapted to move over the openings to close the same, and it will be seen that when the closure is moved to a position indicated by Figure 2 of the drawings, air is admitted to the motor chamber through the opening 12, causing the wheel or motor to rotate in a clockwise direction, but when the closure is moved to close the opening 12, air is admitted through the opening 13, to the end that the wheel or motor is operated in the opposite direction.

Cooperating with the closure 15 is a curved damper 16 supported by the guides 17, that are positioned within the air conduit 6, the damper being provided with an extension 18 which is threaded to accommodate the nut 19, to permit the damper to be secured in various positions of adjustment. The damper 16 controls the passage of air through the conduit 6, and when the damper 16 is moved to a position as indicated by Figure 2 of the drawings, air passes into the conduit 6 at a point adjacent to the upper end thereof, the damper acting to restrict the diameter of the conduit 6 at one point to increase the force of the current of air passing through the conduit 6.

If it is desired to cut off the passage of air through the conduit 6, the damper 20 is operated to cause the edges thereof to closely engage the inner wall of the conduit 6. By moving this damper 20, it will be seen that the diameter of the conduit may be restricted to vary the speed of the wheel or motor.

On one end of the shaft 11 is a power pulley 21 which may transmit motion through the medium of a belt or the like, to any suitable machinery.

Having thus described the invention, what is claimed as new is:

In a device of the character described, a vertical air column, a horizontally disposed conduit in communication with the air column and having an enlarged end forming a motor chamber, a motor operating in the motor chamber, pairs of guides supported within the conduit at a point adjacent to

the motor chamber, a damper positioned between the guides, the damper being of a width less than the width of the conduit to provide a passageway between one edge of the damper and the adjacent wall of the conduit, a closure for controlling the movement of the motor by admitting air at the upper or lower extremities of the motor chamber and a pivoted damper for controlling the passage of air through the conduit.

In testimony that I claim the foregoing as my own, I have hereto affixed my signature in the presence of two witnesses.

HARRY McGRAW.

Witnesses:

ANNA DREITZLER,
E. F. FERRE.
